(57) **CLAIM**

The ornamental design for a mobile phone holder, as shown and described.

DESCRIPTION

1. Mobile phone holder

1.1 : Perspective

1.2 : Front

1.3 : Back

1.4 : Left

1.5 : Right

1.6 : Top

1.7 : Bottom

1.8 : Perspective

This article is a mobile phone holder which can be attached onto the back side of a mobile phone or the back side of a mobile phone case; the part to be protected is displayed as a solid line and the part to be unprotected is displayed as a dotted line; a boundary between the part to be protected and the part to be unprotected is displayed as an alternated long and short dash line.

The dotted lines in Fig. 1.8 showing a mobile phone case illustrate environmental subject matter and form no part of the claimed design.
